[57] CLAIM

The ornamental design for an adapter kit for converting a hot spotting board to a combination hot and cold spotting board for garment cleaning, as shown and described.

DESCRIPTION

FIG. 1 is a front perspective view of an adapter kit for converting a hot spotting board to a combination hot and cold spotting board for garment cleaning, showing my new design;

FIG. 2 is a front elevational view thereof;

FIG. 3 is a back elevational view thereof;

FIG. 4 is a right end elevational view thereof;

FIG. 5 is a left end elevational view thereof;

FIG. 6 is a top plan view thereof;

FIG. 7 is a bottom plan view thereof;

FIG. 8 is an enlarged front perspective view of the upper right end thereof; and,

FIG. 9 is a front elevational view thereof shown attached to a hot spotting board shown in dotted lines. The dotted line illustration of the hot spotting board shown in FIG. 9, is environmental structuring and forms no part of the claimed design.
